ELECTRICAL MEANS FOR OPERATING OR RAISING AND LOWERING RAILWAY BOOMS
AND THE LIKE

Application filed January 24, 1931. Serial No. 511,072.

This invention relates to electrical means for operating or raising and lowering railway booms of the kind commonly employed at level crossings, or to electrically actuated, automatically, or manually controlled, mechanical means for raising and lowering such booms.

The object of the invention is to design an easily operated and controlled efficient means of the nature indicated, which comprises but few working parts, so that the possibility of its becoming disorganized is minimized.

The electrical means according to this invention can be operated either automatically by the train, locomotive, or other vehicle traversing the permanent way or track, as it passes over certain fixed points in the track at opposite sides of the crossing, or manually by suitable switches which can be placed under the control of the signalman and be operated simultaneously with the operation of the signals, or otherwise, or the means can be so arranged that it can be operated manually by any other authorized person.

The means according to this invention can be arranged to operate independently and automatically with each of a plurality of tracks through common power and controlling circuits, or automatically with a single track, or manually with one or a plurality of tracks.

The arrangement is adapted for use with the known mechanical means which are operated by an electric motor to raise and lower the booms, or with any other similar or equivalent means.

In one embodiment of the invention adapted to be operated automatically by the trains traversing the track or tracks, the arrangement is such that should more than one train, et cetera, run on to the portion of the track, or any of the tracks, intermediate the track switch devices or rail contacts, then the booms will be automatically lowered or closed by the first train, et cetera, running on to said portion and remain closed until the last of the trains has run off the portion of its track between the track switch devices, and has operated the track switch or rail contact that closes the power circuit and so raises the booms.

In an arrangement designed to be operated automatically by the train, et cetera, and applied to one or a plurality of tracks the traffic along which passes over the crossing controlled by the booms, a false or supplementary rail is provided for each track, and is arranged alongside and in proximity to one of the rails of the track and insulated therefrom. This false rail extends to within a suitable short distance of both of the track switch devices or rail contacts. 55 60

The means or arrangement includes the controlling circuit in which is placed a pair of solenoids associated with interlocking change-over or reversing switches in the power circuit, which switches may, for example, be in the form of knife contact switches, from which are taken the leads to the reversing motor. The cores or armatures of the solenoids are hingedly connected to a 70 pivoted yoke member, which latter operates, for each solenoid, a suitable switch, such as a knife contact switch. 65 70

The contacts or devices which are operated by and during the travel of certain parts of the boom raising and lowering means, to break the power circuit and so shut off the supply of current to and stop the motor just before the booms reach the limit of their movement in either the raising or lowering 80 direction, are in the controlling circuit, and so are co-operatively combined with the solenoids and the switches which are operated by the pivoted member. 75 80

A relay is provided in the controlling circuit for each of the solenoids operating the main switches, which relays are so arranged that they come into operation, when a train is on the false or supplementary rail, to cut out the rail contacts or track switches. This arrangement ensures that the relay continues to function so long as a train is on the section of the track intermediate the track switches or rail contacts, and so prevents any interference with the controlling circuit by any other train which might enter said section. 90 95 By this arrangement the last train to pass out of the section intermediate the track switches will be the one which will operate the track switch, and by so doing, close the controlling 100 300

circuit to operate the interlocking change-over switch of the power circuit to actuate the motor to raise the booms, and then reverse the motor. Electric switch means are preferably provided and combined with the relays, which means can be operated by hand, if required, say in the case of any emergency rendering it necessary, as in the event of it being desired to operate the booms while a train is standing for some length of time in the protected section intermediate the track switches.

In the case of a plurality of tracks, they may be arranged electrically in parallel, or the electrical connections to the track may be duplicated or be the same for each track.

If the means or arrangement is intended to be operated manually, say from the signal cabin, either automatically with the signals or otherwise, and not by the trains as they run along the track or tracks, then the relays would be dispensed with and suitable switches be provided in the controlling circuit for actuating the solenoids and through them the main interlocked reversing switches of the power circuit. In addition an emergency stop switch may be provided in the controlling circuit to cut off the supply of current to the reversing motor and so prevent further movement of the booms.

The invention will be further explained with the aid of the accompanying drawings, wherein

Fig. 1 is an elevation of the general arrangement of the mechanical means for raising and lowering the booms.

Fig. 2 is a plan view of Fig. 1, the booms being shown in dotted lines.

Fig. 3 is a general arrangement of the electrical means, adapted to be operated automatically by the train.

Fig. 3a is a plan view of a detail of construction of the supplementary rail,

Fig. 4 is a view similar to Fig. 3 adapted for hand actuation, and

Fig. 5 is a sectional fragmentary view showing one way of arranging the false or supplementary rail in relation to one of the rails of the track.

In the general mechanical arrangement illustrated in Figs. 1 and 2, the numerals 1, 2, denote the booms (shown in dotted lines in Fig. 2), which, as usual, are positioned at the crossing at opposite sides of the track or tracks—not shown. The booms 1, 2, are shown pivotally attached, at 3, to standards or supports 4, reference character 5 in Fig. 1 representing the other standards or posts with which the other ends of the booms, 1, 2, engage when lowered to close the crossing, and 6 the counterweights on the rear or shorter arms of the booms 1, 2.

7 is the electric reversing motor in the power circuit α , adapted to be reversed elec-

trically by the interlocking change-over switches.

8 is a casing which encloses the worm and worm-wheel of the transmission and speed reduction means for transmitting motion from the motor shaft 9 through the worm to the worm-wheel on the screw 10. The casing 8 is constructed with a horizontal guiding member 11, which, near its outer end, is carried by a support 12. At its outer end the guide 11 has fixed to it a bearing 13 for the outer end of the screw 10. 14 is a nut which is slidably mounted on the guide 11 and is adapted to be traversed thereon by the screw 10 which works through it. The nut 14 has pivotally attached to it at the sides two parallel bars or members 15, in the form of a frame, between the outer ends of which is fixed a pin 16.

The one boom 1 is operated directly off the rear end of the frame 15 by a link 17, which is pivotally attached to one arm of a bell-crank lever 18, which lever 18 is pivoted at 19 to the post or standard 4, the other arm of the bell-crank lever 18 being pivotally attached to the boom 1, at 20, by the link 21.

The other boom 2 is simultaneously operated off the frame 15 by the pin 16 engaging in the slotted end of one arm of a bell-crank lever 22, which lever is pivotally carried by a support 23. The other arm of the bell-crank lever 22 has pivotally attached to it one end of a rod or link 24, which at its other extremity is pivotally attached to one arm of a similar bell-crank lever 25, which is pivotally carried on a support 26. The other and slotted arm of the bell-crank lever 25 is engaged by a pin 27 carried by a connecting piece 28, which is pivotally attached to a link 29, which latter, at its other end, is pivotally attached to a bell-crank lever 30, 31 being a link connecting the other arm of said bell-crank lever 30 to the boom 2.

The booms 1, 2, are shown in an intermediate position, or substantially midway between the raised and lowered positions. See Fig. 1.

Referring to Fig. 3, in which we illustrate diagrammatically the general arrangement of the electrical means adapted to be operated automatically by the train, et cetera, 32, 33, denote the rails of the permanent way or track. 34 is the supplementary or false rail, which is arranged alongside the rail 33 of the track and is insulated therefrom. In Fig. 5 we show a convenient way of arranging the false or supplementary rail 34 in relation to the rail 33 of the track and of insulating it therefrom. The supplementary rail 34 is shown in the form of a bar carried by the rail 33 at a suitable distance therefrom at one side thereof, and attached thereto by bolts 34a. 34b are washers of insulating material placed round the bolts 34a in the holes through the rail 33. 34c is one of the wheels of the vehicle or train, shown bridging across

130

the main rail 33 and supplementary rail 34, so that when a vehicle or train is in the section under control the current can pass through the wheels and axles of the vehicle or train between the supplementary rail 34 and the other main rail 32. To preclude the possibility of any vehicle passing over the crossing 34a—see Fig. 3a—from short-circuiting the supplementary rail 34 and the track, the rail 34 does not extend across the crossing, but terminates at both sides of the crossing and the ends of the sections are joined by an insulated underground cable 34b.

35, 36 are the power mains, and 37 is the reversing motor. 38, 39 are the interlocking change-over or reversing switches positioned in the power circuit *a*, intermediate the mains 35, 36 and the motor 37, which switches 38, 39, operate to control the flow of the supply of current from the generator 43 to the motor 37 in both directions. 40 represents the movable knives and 41 the fixed contacts of the switches 38, 39. The movable knives 40 are attached to and carried by cross-pieces 42 connected to and insulated from the armatures or cores 44 of the solenoids 45, 46. 45a, 46a, are springs which are placed under compression when the core of the corresponding solenoid is moved to close the power circuit through the switch 38 or 39, and operate, when the solenoid is de-energized, to open the power circuit.

47 is the battery or source of supply of current for the controlling circuit *b*.

48 is the yoke member, pivoted at 49, and connected at its extremities by links 50, 51, to the armatures or cores 44 of the solenoids 45, 46. The yoke member 48, at its ends, carries the movable knives 52, 53, which are adapted to make contact with the fixed contacts 54, 55.

56, 57, are the mechanical contact devices which are operated during the travel of the nut 14 on the screw 10, when the latter nears the end of its movement in both directions. For this purpose a suitably curved plate or cam 58 is fixed to one of the trunnions of the nut 14 in such a position as slidingly to engage with the contact devices 56, 57, just before it completes its travel on the screw 10 in the respective directions of movement. The contact devices 56, 57—see Figs. 2 and 3 of the drawings—each co-operate with a pair of contacts 59, 60 and 61, 62, respectively, to stop the motor and reverse it.

63, 64, represent the track switches or rail contacts, which may conveniently be in the form of mercury splash switches and are adapted, by the passing of the train over the track rails 32, 33, to close the controlling circuit *b* to energize one of the solenoids 45 or 46, and so operate the interlocking change-over or reversing switches 38, 39, and by doing so, to close the circuit *a* to drive the motor in

the requisite direction to operate the booms 1, 2.

65, 66 are the two relays, and 67, 68 the armatures which, when the train is in contact with the supplementary rail 34, are attracted by the energized relays 65, 66, and break the controlling circuit *b*, and prevent any other train or trains which may enter the section between the track switches, or any train but the last that may leave said section, from closing the controlling circuit *b* to operate the motor.

69 is the push button or switch which co-operates with the two contacts 70, 71, to ensure the one control 70 cutting out the relay 66, and the other 71 closing the controlling circuit to energize one or other of the solenoids 45, 46, and so operate the motor and the booms 1, 2, in case of any emergency rendering it necessary.

In the operation of this embodiment of the invention, the train which last passed through the section will have actuated the means to open or raise the booms 1, 2, and in doing so will have caused the cam 58 to contact with and depress the contact device 57. If the next succeeding train approaches the crossing in the direction which causes it to operate the switch 63, then the controlling circuit *b* energizes the solenoid 45 through switch 63, lead or conductor *c*, armature 67, contact 62, lead *d*, contact 59 and lead *e* to the solenoid 45, the circuit being completed by way of leads *f* and *g*, through the battery 47, leads *h* and *i*, and rail 32 to the switch 63. This energizing of the solenoid 45 attracts the core or armature 44 and causes the movable knives 40 to make contact with the fixed contacts 41 of the change-over switch 38, which makes the circuit between the generator 43 and motor 37 through lead 36, switch 38, lead *k*, motor 37, lead *j*, switch 38 and lead 35. The attraction of the core or armature 44 also makes the contact between the movable knife 52 and the fixed contact 54, and this switch operates through yoke member 48, lead *i*, lead *h*, battery 47, lead *f*, solenoid 45, lead *e*, contact 59 and lead *d*, to keep the solenoid 45 energized after the train has actuated the switch 63 and before it comes into contact with the auxiliary rail 34, until the booms 1, 2, have been lowered and the cam 58 has depressed the contact 56 to reverse the motor 37.

This operation of switch 38 causes the motor to run in a direction to traverse the nut 14 in the direction of the contact device 56, and in doing so to lower the booms 1, 2. Any further trains entering the section will not operate the controlling circuit, and the booms 1, 2, will remain lowered or closed owing to the breaking of the controlling circuit *b* by the relays 65, 66, when the train is in contact with the supplementary rail 34. The relays 65, 66, are placed in circuit with

70

75

80

85

90

95

100

105

110

115

120

125

130

and adapted to be energized by the battery 47 when the rail 32 of the track is electrically connected with the supplementary rail 34 through the wheels—which traverse the rails 32, 33 and 34—and axles or other metal parts of the vehicles of the train. One leg *i* of the relay circuit is connected to the rail 32, and the other *l*, *l*¹, to the auxiliary rail 34, so that the relay circuit is made and the relays 5 act to break the main circuit when a train is in contact with the supplementary rail 34 by current passing from the battery 47, through leads *g*, *m* and *m*¹, relays 65, 66, (which retract the armatures 67, 68, to break the circuit 10 *b*), leads *l*, *l*¹, supplementary rail 34, the wheels and axles of the train, main rail 32, and leads *i*, *h*, to the battery. Just before the booms 1, 2, reach the closed or horizontal position, the cam 58 engages the contact device 15 56 and stops the motor 37, by breaking the contact at 59, and makes the contact at 60 to reverse the motor when the solenoid 46 is energized by the operation of the switch 64.

If there are a number of trains in the section 20 between the track switches 63, 64, these, with the exception of the last one, will pass out of the section without affecting or interfering with either the controlling or power circuits as the controlling circuit is broken 25 by the relays 65, 66, while any train is in contact with the supplementary rail 34, the booms will remain in the lowered or closed position until the last train to leave the section operates the track switch 64, whereupon 30 the solenoid 46 will be energized and the core or armature 44 thereof be attracted and operate the interlocking change-over switch 39 and switch 53, 55, to close the power circuit *a* and drive the motor 37 to raise the booms 35 1, 2. Upon operation of the switch 64 by a train leaving the section, the controlling circuit *b* energizes the solenoid 46 through switch 64, leads *n* and *d*, contact 60, leads *o* and *c*, contact 61, and lead *p* to the solenoid 46, the 40 circuit being completed through leads *q*, *f* and *g* to the battery 47, and thence through leads *h* and *i*, and rail 32 to the switch 64. The passage of the last train off the rail 34 by 45 breaking the electrical contact between rails 34 and 32 causes the relays 65, 66, to be de-energized, so that the armatures 67, 68, close the controlling circuit *b*.

During the raising of the booms 1, 2, the nut 14 traverses the screw 10 in the direction 50 of the contact device 57, and the cam 58 contacts with said device just before the booms reach the raised position. The contact of the cam 58 with the contact device 57 again stops the motor 37 and makes the contact at 62 to reverse the motor 37 when the solenoid 45 is again energized.

This cycle of operations is repeated when the switch 63 is actuated by the next incoming train.

65 As will be understood, in the event of a

train entering the section between the track switches 63, 64, and first passing over track switch 64, the arrangement will operate in the same manner to actuate the motor 37 to lower the booms 1, 2, and reverse the motor, 70 through the controlling circuit *b*, by way of switch 64, leads *n* and *d*, contact 59 and lead *e* to the solenoid 45, and thence by leads *f* and *g*, battery 47, leads *h* and *i*, and rail 32 to switch 64. The energized solenoid 45 will 75 then operate the change-over switch 38, as previously described, to close the power circuit *a*, in order to drive the motor 37 to lower the booms 1, 2. The knife contact switch 52, 80 54, will also be actuated, as previously described, to keep the circuit *b* closed after the train has actuated switch 64 and before it comes into contact with the auxiliary rail 34, until the booms 1, 2, have been lowered and cam 58 has depressed the contact 56 to reverse the motor 37, the circuit being made as described in connection with the operation of switch 63.

Upon the train leaving the section it will 85 actuate the train switch 63, which will energize solenoid 46 to operate change-over switch 39 and knife contact switch 53, 55, to drive the motor 37 to raise or open the booms 1, 2. The circuit to energize the solenoid 46 in this case is made through switch 63, lead 90 *c*, contact 61, and lead *p* to the solenoid 46, and thence by leads *q*, *f* and *g*, battery 47 leads *h* and *i* and rail 32 to switch 63. The knife contact switch circuit to keep the solenoid 46 energized until the booms 1, 2, have 95 been raised, in this case is made by way of movable contact 53, yoke member 48, leads *i* and *h*, battery 47, leads *g*, *f*, *q*, solenoid 46, lead *p*, contact 61 and lead *c* to the fixed contact 55. 100

The emergency switch 69 is used under the conditions and operates in the manner previously explained to allow the booms 1, 2, to be actuated whilst one or more trains are standing on the track in the section intermediate the track switches 63, 64. 105

In the arrangement represented in Fig. 4 of the drawings, which is designed to be operated manually, the power and controlling circuits *a*, *b*, respectively are the same, or substantially the same, as in the arrangement described in connection with Fig. 3, and the same numerals of reference will serve to indicate the same or corresponding parts. As shown, the track switches and relays are dispensed with. In the controlling circuit *b* there are interposed the manually operated push button switches 72, 73, the one for operating the interlocking change-over switch to close the power circuit to operate the motor 37 to lower the booms 1, 2, and the other to close the power circuit to operate the motor 37 to raise the booms 1, 2. 110 120 125 74 is an emergency switch to enable the motor 37 to be stopped to arrest the movement 120 125 130

of the booms 1, 2, in any position. The manner in which this form of the invention operates will be apparent from the detailed description of the operation of the arrangement described in connection with Fig. 3.

What we claim as our invention and desire to protect by Letters Patent is:—

1. Means for automatically raising and lowering railway booms and the like, including, in combination, an electric power circuit, a reversing motor in said power circuit, a pair of interlocking change-over switches each adapted alternately to control the power circuit, mechanical means which are operated by the motor to raise and lower the booms, means actuated by said mechanical means for stopping the motor when the booms are raised or lowered and ensuring its rotation in the opposite direction when the interlocking change-over switches are again operated, an electric circuit for controlling the power circuit including a solenoid for each of said change-over switches, track switches in the controlling circuit at each side of the crossing, a relay circuit, and means in said relay circuit intermediate the track switches with which means the train contacts and, by closing the relay circuit, breaks the controlling circuit, as set forth.

2. Means for automatically raising and lowering railway booms and the like, including, in combination, an electric power circuit, a reversing motor in said power circuit, a pair of interlocking change-over switches each adapted alternately to control the power circuit, mechanical means which are operated by the motor to raise and lower the booms, means actuated by said mechanical means for stopping the motor when the booms are raised or lowered and ensuring its rotation in the opposite direction when the interlocking change-over switches are again operated, an electric circuit for controlling the power circuit including a solenoid for each of said change-over switches, track switches in the controlling circuit at each side of the crossing, and a pair of further switches which are also operated by the solenoids simultaneously with the change-over switches and close the controlling circuit independently of the track switches until said circuit is broken by the mechanical means to stop the motor, as set forth.

3. Means for automatically raising and lowering railway booms and the like, including, in combination, an electric power circuit, a reversing motor in said power circuit, a pair of interlocking change-over switches each adapted alternately to control the power circuit, mechanical means which are operated by the motor to raise and lower the booms, means actuated by said mechanical means for stopping the motor when the booms are raised or lowered and ensuring its rotation in the opposite direction when the inter-

locking change-over switches are again operated, an electric circuit for controlling the power circuit including a solenoid for each of said change-over switches, track switches in the controlling circuit at each side of the crossing, a pair of further switches which are also operated by the solenoids simultaneously with the change-over switches and close the controlling circuit independently of the track switches until said circuit is broken by the mechanical means to stop the motor, a relay circuit, and means in said relay circuit intermediate the track switches with which means the train contacts and, by closing the relay circuit, breaks the controlling circuit, as set forth.

4. Means for automatically raising and lowering railway booms and the like, including, in combination, an electric power circuit, a reversing motor in said power circuit, a pair of interlocking change-over switches each adapted alternately to control the power circuit, mechanical means which are operated by the motor to raise and lower the booms, means actuated by said mechanical means for stopping the motor when the booms are raised or lowered and ensuring its rotation in the opposite direction when the interlocking change-over switches are again operated, an electric circuit for controlling the power circuit including a solenoid for each of said change-over switches, track switches in the controlling circuit at each side of the crossing, a pair of further switches which are also operated by the solenoids simultaneously with the change-over switches and close the controlling circuit independently of the track switches until said circuit is broken by the mechanical means to stop the motor, a relay circuit, and a supplementary rail in the track section between the track switches and in the relay circuit which, by closing the relay circuit when a train is in the section, breaks the controlling circuit, as set forth.

In testimony whereof we have signed our names to this specification.

ARTHUR BUTTERWORTH.
NILS JOHN VIKEN.
